UNITED STATES PATENT OFFICE

ALFRED F. FUKAL, OF CHICAGO, ILLINOIS, ASSIGNOR TO CHICAGO FLEXIBLE SHAFT COMPANY, OF CHICAGO, ILLINOIS, A CORPORATION OF ILLINOIS

DESIGN FOR A COMBINED BASE AND BOWL STAND FOR A COFFEE MAKER

Application filed March 24, 1933. Serial No. 47,573. Term of patent 7 years.

To all whom it may concern:

Be it known that I, ALFRED F. FUKAL, a citizen of the United States, residing at Chicago, in the county of Cook and State of Illinois, have invented a new, original, and ornamental Design for a Combined Base and Bowl Stand for a Coffee Maker, of which the following is a specification, reference being had to the accompanying drawing, forming part thereof.

In the drawing—

Figure 1 is a side elevation of a combined base and bowl stand for a coffee maker, showing my new design, and

I claim:

The ornamental design for a combined base and bowl stand for a coffee maker, substantially as shown.

ALFRED F. FUKAL.
